SHEET-ENGAGING ROLLS

John D. Robertson, Taunton, Mass., assignor to Mount Hope Machinery Company, Taunton, Mass., a corporation of Massachusetts

Filed Jan. 13, 1955, Ser. No. 481,531

1 Claim. (Cl. 29—116)

This invention relates to improvements in sheet-engaging rolls and methods of providing wear-surfaces thereon. More particularly, the invention provides an improved roll structure wherein the wear-surface of the roll is provided by a homogeneous body of wound and over-lapped soluble strip-material which is applied with a solvent and whose over-lapping convolutions become partially dissolved and homogeneously merged in a manner to substantially eliminate objectionable seams when the solvent evaporates.

Rolls used in the textile, paper, and other industries for guiding sheet materials, and for lateral expansion or contraction of engaged sheet materials, frequently are subjected to surface wear to an extent which may make it desirable to be able to renew the surface of any particular roll. This is particularly true in the case of longitudinally curved expander rolls which customarily have a flexible surface sleeve which is required to rotate about the curved axis of the roll.

It is among the objects of the present invention to provide a roll whose surface portion may be relatively easily renewed without the inconvenience and delay heretofore involved when a worn roll had to be returned to the manufacturer for re-surfacing.

Another object of the invention is to provide a roll re-surfacing method whereby a roll may be re-surfaced by any reasonably intelligent person who follows a few simple instructions.

A further object of the invention is to provide a roll having a surface portion made up of helically wound soluble strip material which may be wound on a roll with simultaneous application of a solvent thereto or to the surface portion upon which the strip material is being laid, whereby a uniformly thick homogeneous surface covering is attained which becomes stable and wear-resisting and free of objectionable ridges upon evaporation of the solvent.

Yet another object of the invention is to provide a roll having a sleeve of soluble material and having soluble strip material helically wound on the sleeve with predetermined over-lapping of the convolutions, the said sleeve material and strip material being subjected to the action of a solvent during the process of winding the strip material thereby to attain a homogeneous roll-surfacing body which becomes substantially free of objectionable ridges and highly wear-resisting upon evaporation of the solvent.

It is, moreover, my purpose and object generally to improve roll structures and methods of renewing roll surfaces, and especially the structures and surfaces of longitudinally curved expander rolls, and the like.

In the accompanying drawing:

Fig. 1 is an elevational view of a longitudinally curved expander roll having a surface structure embodying features of the invention;

Fig. 2 is an elevational view of an end portion of a roll similar to that of Fig. 1 illustrating the method of re-surfacing the roll, portions being in medial cross-section,

2

and the scale being substantially larger than that of Fig. 1;

Fig. 3 is an elevational view showing opposite end portions of the roll of Fig. 1 on the scale of Fig. 2;

Fig. 4 is an elevational view of a fragment at one end of the roll of Fig. 3, showing the homogeneous nature of the applied roll surface;

Fig. 5 is a view generally similar to Fig. 4 but showing a modified form in which both the wound surfacing material and the sleeve on which it is wound are of a nature to merge into a homogeneous mass;

Fig. 6 is a view generally similar to Fig. 2 but showing a modified form of the invention in which the edges of successive convolutions of the surfacing strip material are butted;

Fig. 7 is a fragmentary elevational view of the central portion of a roll wound with butted edges, as in Fig. 6, and showing the outer layer of convolutions laid with opposite pitch on opposite sides of the center of the roll; and

Fig. 8 is a view generally similar to Fig. 4 but showing the butted convolutions of the Figs. 6 and 7 embodiment of the invention.

Referring to the drawings, a longitudinally curved 25 expander roll is shown at 10 in Fig. 1, it having a curved axle 12 which projects at each end of the roll body to facilitate mounting of the roll on a suitable support by means of clamps, or the like (not shown).

The invention has to do with the surface structure of 30 rolls and a method of re-surfacing rolls, and it should be understood that the illustrated roll is representative of sheet-engaging rolls generally regardless of whether they are straight from end to end or longitudinally curved.

35 The illustrated roll has a series of spools or roll sections 14 distributed in slightly spaced relation along the axle 12 with suitable anti-friction bearing means, as at 13 in Fig. 3, intervening between the roll sections and the axle whereby the roll sections 14 are freely rotatable on 40 the axle 12. Spacing members 13^a maintain the spacing of the bearing means and roll sections in conjunction with end members 13^b which are secured to the axle 12. A sleeve 16 of flexible material embraces all of the roll sections 14, tying them together for rotation in unison 45 with the sleeve 16. End caps 18, 20 are removably fixed to the adjacent end-most roll sections 14, as at 19 in Fig. 3.

According to the invention as represented in the embodiments of Figs. 1 through 5 of the drawings, the 50 surface portion of roll 10 is formed of strip material which is helically wound on sleeve 16 with each succeeding convolution substantially over-lapping the preceding convolution.

Referring to Fig. 2, the surfacing strip material 22 55 is shown in the form of relatively thin tape having substantial width. Tape 2" wide and $\frac{1}{32}$ " thick may be wound on sleeve 16 with approximately $1\frac{1}{2}$ " overlap of successive convolutions. This builds up to four thicknesses of the tape as the fourth and subsequent convolutions are laid in place.

When a roll is to be provided with a wearing surface in accordance with the teachings of the invention, a temporary end member 24 is secured to the end-most spool or roll section 14 (Figs. 2 and 6) at each end of the roll. 65 One of the end members 24 is illustrated in Fig. 2, and also in Fig. 6, as having an inwardly extending annular flange 25 for engaging a similar flange 15 on the adjacent end-most spool or roll section 14, with removable fastening means 25' securing the flanges 25, 15 together, so that member 24 constitutes a temporary extension of the end-most spool or roll section 14. A sleeve element 24^a 70

on member 24 constitutes a temporary extension of the roll sleeve 16 having outside diameter approximating that of sleeve 16. In the embodiments of Figs. 1-5, the first convolution of the strip material or tape 22 may be laid directly on the sleeve element 24^a of one of the members 24, as at 22' in Fig. 2, with next succeeding convolutions substantially overlapping the preceding convolution. Assuming material 2" wide with an overlap of each convolution approximating 1½", the fourth-laid convolution will have built up the covering to four thicknesses of the tape at the lefthand ½" margin of the said fourth-laid convolution. Each succeeding convolution after the fourth-laid one builds up another ½" of covering to four thicknesses of the tape until the entire length of the roll is covered by four thicknesses of the tape. Each convolution is depressed to provide a shoulder or shoulders at the location or locations of an overlapped edge or overlapped edges of one or more previously laid convolutions, which results in a stepped form of convolutions wherein the steps approximate ½" in width and are located at different radial distances from the roll axis. Each said step of an already laid convolution constitutes a seat for a ½" wide portion of the next succeeding convolution, with an edge of the convolution which is being laid positioned relatively close to a said shoulder formed by the next preceding convolution. Each successive convolution extends approximately ½" beyond the overlapped edge of the previously laid convolution and becomes depressed over the said edge of the previously laid convolution in contact with the surface of the sleeve 16 or with an underlying portion of the previously laid convolution. Hence, the second, third and fourth convolutions all become depressed at the location of the overlapped edge of the first-laid convolution which provides an exterior relatively slight spiral shoulder 22^a approximately ½" inward from the left-hand edge of the fourth-laid convolution 22", Fig. 2. The fifth convolution 22''' is laid upon depressed portions of the fourth-laid convolution 22" with its left-hand edge closely adjacent to the said shoulder 22^a. It will be apparent from Fig. 2 that the inner edges of successive convolutions occur at approximately ½" intervals along the surface of sleeve 16, and an outer helical shoulder 22^a is provided at each so that the successive convolutions each as a portion approximately ½" in width at the outer surface of the tape-wound roll, and all of these surface portions of convolutions combine to produce a roll surface which is devoid of objectionable ridges or seams. The winding as shown in Fig. 2 may be continued throughout the length of sleeve 16 and onto the end member 24, at the end opposite to that seen in Fig. 2, sufficient to provide a four thicknesses coating beyond the adjacent end of sleeve 16.

The strip or tape 22 may be made of any suitably flexible and wear-resisting material, and any suitable adhesive may be provided, either on the tape or applied during the laying of convolutions for maintaining the surface covering in its helically wound condition.

After the strip or tape 22 has been wound as described in connection with Fig. 2, starting on one member 24 and ending on the other, the temporary members 24 may be removed and the portions of the surface material projecting beyond the ends of sleeve 16 may be trimmed away, after which the regular roll end caps 18, 20 may be secured in place to put the roll in readiness for service.

While various materials may be employed for the surfacing tape, such as rubber with or without fibrous reinforcement, I presently consider it preferable to employ one of the available soluble plastic materials which, in strip or tape form may be helically wound, with addition of a suitable solvent, whereby a wound roll covering, through the action of the solvent, becomes a homogeneous body. Tape 22 made of vinyl chloride may be used with satisfactory results, in which case the solvent, indicated at 23 by stippling, may be a fifty-fifty solution of methyl ethyl ketone and cyclohexanone, which may be applied

to the outer surface of the tape during the process of winding the tape on a roll sleeve 16. Obviously, particular conditions to which any particular roll may be subjected in service will dictate to a considerable degree the nature of the roll-surfacing tape which will be employed.

In Fig. 2, it is not contemplated that the wound strip material or tape 22 will become strongly adhered to the roll sleeve 16, whether or not the convolutions are merged into a homogeneous mass by the action of an introduced solvent. Hence, when it becomes necessary or desirable to renew the surface of a roll as herein shown, the strip material or homogeneous mass may be cut or otherwise removed from sleeve 16 preparatory to re-surfacing of the roll. However, when a soluble tape material and solvent are employed for re-surfacing, the sleeve 16 may, if desired, be of the same material as the strip material or tape 22, or a related material, so that the solvent will act on the material of sleeve 16 as well as on the tape material thereby to render the sleeve and tape homogeneous as in Fig. 5. In such a case, evaporation of the solvent leaves a relatively hard and tough homogeneous surface mass, and any re-surfacing would need to be preceded by a grinding away of the worn coating to provide a suitable sleeve surface for reception of the re-surfacing tape windings.

Fig. 6 illustrates a modification in which the surfacing tape is helically wound in successive layers with the tape edges of the convolutions in each layer butted. The convolutions 221 of the inner layer may be laid with pitch of the convolutions in one direction and the convolutions in the second layer may be laid with pitch of the convolutions in generally opposite direction. The convolutions of the third layer may be laid the same as those of the inner layer. The butted edges are indicated at 223.

The outer layer, however, preferably has its convolutions laid with those on one side of the center of the roll pitched to the right and those on the other side of the center of the roll pitched equally to the left, as represented in Fig. 7, wherein two separate strips 222, 222' have their inner end portions tapering to a point at 222^a, 222^b, respectively, so that these tapered ends may be laid at the center of the roll with edges butted at 222^c, and the strips wound helically from the center of the roll outwardly in opposite directions. This avoids a surface appearance which might suggest an action by the roll on sheet material tending to cause lateral travel of the sheet material in one direction or the other.

In the Figs. 6 and 7 embodiment, a solvent is applied between the convolutions of successive layers to attain a generally homogeneous surfacing mass as illustrated in Fig. 8, which is generally the same as in the Figs. 1-4 embodiment. When desired, the solvent may be introduced also between the inner layer and the member 16 on which the strip material is wound when the latter material is of a nature to be merged with the strip material as described in connection with Fig. 5.

It is intended that the patent shall cover, by suitable expression in the appended claim, whatever features of patentable novelty exist in the invention disclosed.

I claim as my invention:

A roll having a longitudinally curved axle, a sleeve element of flexible material extending from end to end of the roll, rotatable on said curved axle, and constituting a relatively permanent element of said roll, a relatively wide continuous strip of wear-resisting soluble material helically wound on said sleeve element from end to end thereof with each succeeding convolution over-lapping a substantial portion of the width of the next preceding convolution, each of said convolutions having a substantial portion of its width exposed at the surface of the roll and said convolutions, excepting an endmost one, each having a plurality of other substantial portions of its width disposed at different radial distances outward from the roll axis and over-lapped by portions of subsequently laid convolutions, said sleeve

element having a surface portion of soluble material compatible with the soluble material of said strip material, said over-lapped and over-lapping convolutions of soluble material and said soluble surface portion of said sleeve element being dissolved and merged into a substantially homogeneous wear-resisting surface mass extending around and from end to end of said roll.
